UNITED STATES PATENT OFFICE.

DAVID KANE, OF BROCKTON, MASSACHUSETTS.

DESIGN FOR A BADGE.

SPECIFICATION forming part of Design No. 25,545, dated May 26, 1896.

Application filed March 21, 1896. Serial No. 579,658. Term of patent 7 years.

To all whom it may concern:

Be it known that I, DAVID KANE, a citizen of the United States, residing at Brockton, in the county of Plymouth and Commonwealth 5 of Massachusetts, have invented and produced a new and original Design for a Badge, of which the following is a specification.

My invention relates to a new and original design for a badge or similar article; and it 10 is designed to be worn as a pin, button, and the like.

In the drawings the badge is shown as being made in the form of a pin.

Figure 1 is a front elevation of the badge, 15 showing my design upon an enlarged scale, and Fig. 2 is a side elevation of same.

The leading features of my design consist in a badge shaped to represent three triangles

placed in line. The apex of each of the upper two triangles extends into and is a part 20 of the triangle next below it. Each triangle is ornamented by side lines and milled edges, and the triangles of triplicate character constitute a unitary design as a complete article of manufacture.

What I claim is—

The design for a badge or similar article, substantially as herein shown and described.

In testimony whereof I have signed my name to this specification in the presence of 30 two subscribing witnesses.

DAVID KANE.

Witnesses:

E. FRANK. WOODBURY,
GEORGE L. DOLBEARE.
